(57) **CLAIM**

The ornamental design for a golf club loft and lie instructional tool, as shown and described.

DESCRIPTION

FIG. 1 is a perspective top right view of the golf club loft and lie instructional tool, showing my new design;

FIG. 2 is a perspective top left view thereof;

FIG. 3 is a perspective bottom right view thereof;

FIG. 4 is a front side view thereof;

FIG. 5 is a back side view thereof;

FIG. 6 is a left side view thereof;

FIG. 7 is a right side view thereof;

FIG. 8 is a top side view thereof; and,

FIG. 9 is a bottom side view thereof.

The dashed lines indicate boundary areas and are not part of the claimed design.
